JACK

Clarence M. Donahoo, Detroit, Mich., assignor of one-fourth to Donald McElderry and one-fourth to Frank R. McElderry, both of Ottumwa, Iowa

Application April 19, 1941, Serial No. 389,425

3 Claims. (Cl. 254—1)

This invention relates to a jack, and it is an object of the invention to provide a jack having a flexible leg comprising a plurality of links, together with means for automatically locking or unlocking adjacent links of the leg as required in the use of the jack.

Another object of the invention is to provide a jack including a housing into which a jack leg is retracted when not in use, together with means for moving said leg outwardly of the housing for effecting a lifting operation, the entrance end portion of the housing being angularly related with respect to the remaining portion of the housing and the leg being articulated to facilitate the movement of the leg outwardly or inwardly with respect to the housing.

An additional object of the invention is to provide a jack comprising a housing having an angularly disposed end portion together with an articulated leg movable into or out of the housing, said leg comprising links having associated therewith means whereby adjacent links when extended from within the housing are substantially rigidly locked one to the other.

The invention consists in the details of construction and in the combination and arrangement of the several parts of my improved jack whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein—

Figure 1 is a view in top plan of a jack constructed in accordance with an embodiment of my invention and unapplied;

Figure 2 is a longitudinal sectional view taken substantially on the line 2—2 of Figure 1 with certain of the parts in elevation;

Figure 3 is a detailed sectional view taken substantially on the line 3—3 of Figure 2;

Figure 4 is a detailed sectional view taken substantially on the line 4—4 of Figure 2;

Figure 5 is a detailed sectional view taken substantially on the line 5—5 of Figure 2;

Figure 6 is a detailed sectional view taken substantially on the line 6—6 of Figure 2;

Figure 7 is a view in perspective of a locking key as herein comprised unapplied;

Figure 8 is a fragmentary view partly in sec-

tion and partly in elevation illustrating a slightly modified form of invention;

Figure 9 is a fragmentary detailed view of the inserted end portion of the leg as herein embodied;

Figure 10 is a longitudinal sectional view taken through one of the links of the articulated leg.

As disclosed in the accompanying drawings, 1 denotes a section of a housing H. This section 1, as herein disclosed, is angular in cross section and has one end closed, as at 2. This section 1 of the housing is adapted to be anchored in any desired manner to a suitable supporting structure, it only being required that such section 1 have its longitudinal axis disposed substantially horizontal.

The bottom wall 3 of the section 1 from substantially one end to the other of the section 1 is formed to provide a depending trough-like guide 4 in which extends an elongated lug 5 carried by and depending from a block 6. As is particularly illustrated in Figure 2 of the drawings, this block 6 is of a length in excess of the length of the lug 5 and said block 6 has a flat upper face in close contact with the flat top wall of the section 1, as at 7. The end portion of the guide 4 remote from the closed end 2 of the section 1 is closed by a relatively thick end wall 8 which provides a mounting, as at 9, for an end portion of a threaded shaft 10. This shaft 10 threads lengthwise through the lug 5 of the block 6 and has an end portion disposed through the bearing 11 carried by the closed end 2 hereinbefore referred to. Coacting with the wall 8 and the bearing 11 are the thrust collars 12 fixed to the shaft 10, thus assuring the shaft 10 being effectively held against endwise movement. The portion of the shaft 10 extending beyond the closed end 2 of the section 1 is adapted to be coupled in any desired manner to a suitable source of power. As illustrated in the accompanying drawings, this extended portion of the shaft 10 carries a gear 14 for such purpose although I do not wish to limit myself in this respect.

Suitably secured, as at 15, to the open end of the section 1 of the housing H is a second section 16. The section 16 when assembled with respect to the section 1 is in continuation of said section 1. This section 16 has its end portion a immediately adjacent to the section 1 arcuate in form and disposed on a desired radius while the opposite end portion b of the section 16 is straight and elongated. The length of the arcuate portion a of the section 16 is such as to position the portion b substantially at right angles to the longi-

tudinal axis of the section 1. This portion *b* of the section 16 is also disposed downwardly with respect to the section 1. The upper or arcuate portion *a* of the section 16 is provided along its upper wall with a reinforcing web 17 and formed with this web 17 and the adjacent portion of the outer wall of the portion *b* is a plate 18. This plate 18 is of such dimensions preferred and, as herein disclosed, extends a material distance beyond opposite sides of the housing H whereby said plate provides means for effectively mounting the housing H on a suitable supporting structure.

It is believed to be obvious that if desired a securing or anchoring means may also be employed in connection with the closed end portion of the section 1 of the housing. As this is an obvious expedient it is not believed that a detailed description and illustration of such additional support are necessary.

Working within the housing H is an articulated leg L comprising a plurality of links 19 and an outer end link 20. Each of the links 19, as herein disclosed, is substantially solid and is provided at one end at its transverse center with a mortise or groove 21 and at its opposite end with an outstanding lug or tenon 22. The lug or tenon 22 of one link is substantially snugly received within the mortise or groove 21 of an adjacent link and disposed through these interfitting portions of adjacent links closely adjacent to the bottom faces of the links is a pivot member 24 whereby said adjacent links are connected for relative swinging movement so that the leg L may readily have desired movement lengthwise of the housing H and particularly through the curved or arcuate portion *a* of the section 16. The mortise or groove 21 of the innermost link of the leg L substantially snugly receives a lug or tenon 25 extending from the block 6. This lug 25 and adjacent end link 19 are pivotally connected by the pin 26.

The mortise or groove 21 in an end portion of each of the links 19 provides a pair of transversely spaced arms 27 and the inner face of one of the arms 27 is provided with an elongated groove 28 at right angles to the pivotal connection of said arm with the lug or tenon 22 of an adjacent link 19. When adjacent links 19 are substantially aligned, this groove 28 registers with the head portion 29 of a T slot disposed through the associated lug or tenon 22. The leg portion 30 of this T slot, as hereinbefore disclosed, is at substantially the longitudinal center of the head portion 29 and extends inwardly of the link.

The side faces of the links 19 are provided therewith along with the grooves or channels 31 and when adjacent links 19 are aligned, said grooves or channels 31 are aligned and for a purpose to be hereinafter more particularly referred to.

The arm 27 of each of the links 19 having the groove 28 is provided therethrough at the central portion of said groove 28 with an opening 32 which is also in communication with the adjacent groove or channel 31.

Coacting with each pair of adjacent links 19 is a locking member or key M. The key M, as herein disclosed, comprises a flat plate 33 which snugly and slidably engages within the slot 29 of the lug or tenon 22 of the link 19. This plate is also, as herein disclosed, of a width substantially equal to the width of the lug or tenon 22 so that when not in locking position the plate 33 will offer no hindrance or obstruction to the relative swinging movement of the adjacent links. 75

However, upon shifting of the plate 33 toward an adjacent arm 27 provided with the groove 28 an end portion of said plate 33 will enter said groove 28 and thereby effectively lock and hold the adjacent links 19 against swinging movement. When the plate 33 is at the limit of its holding or locking position it does not intersect the adjacent groove or channel 31.

It is also to be stated that the openings 32 are not essential and if preferred each of the grooves or channels 28 may be closed at the end adjacent to groove 31. The openings 32, however, facilitate the cleaning out of foreign matter when the occasion arises.

15 The plate 33 at one end thereof and at its transverse center is provided with a rearwardly disposed stem 34 of a length substantially equal to the length of the supplemental slot 30, and the outer end portion of this stem 34 is provided with the oppositely directed arms 35 and 36 which have outward movement beyond opposite sides of the inner ends of the slot 30. The arms 35 and 36 are each of such length that when the plate 33 is at the limit of its movement in one direction, one of said arms extends within a groove or channel 31 at one side of the link 19 and with the outer arm free of the groove or channel 31 at the opposite side.

The outermost link 20 is operatively engaged 30 with the adjacent link 19 in the same manner as hereinbefore set forth with respect to adjacent links 19. This link 20, however, is provided at its outer end with an extended tongue 36. As indicated by broken lines in Figure 2, this tongue 36 is operatively engaged within a socket 37 carried by a foot plate 38.

The adjacent links 19 of the leg L when retracted within the housing H are unlocked so that as the leg L moves outwardly said adjacent links 40 19 will have the required relative swinging movement. The adjacent links within the housing H have the arms 36 within the grooves or channels 31 at the same side of the links with, of course, the second arms 35 fully retracted. As 45 the links move outwardly beyond the entrance end of the section 16 of the housing H, the extended extremities of the arms 36 will contact with an inwardly disposed cam 39 carried by the side wall of the section 16 at a point closely adjacent to the lower or entrance end of said section 16. This contact of an arm 36 with the cam 39 will cause the plate 33 to be shifted in a direction to engage within the groove 28 of a lug or tenon 22 of an adjacent link 19 whereby said adjacent 50 links are effectively locked so that as the links 19 of the leg L pass down below the lower or entrance end of the section 16 of the housing H they are rigidly held so that said extended portion of the leg is rigid. Upon this movement of the plate 33, the arm 35 will be extended within the groove or channel 31 at the opposite side of the link 19 so that as the leg L is retracted within the housing H and after the arms 35 and 36 have passed inwardly beyond the cam 39, the extended 55 end of the arm 35 will contact a second cam 40. This will result in shifting of the plate 33 out of locking position and thus allow the desired flexing or articulation of the leg as it passes through the curved or arcuate portion *a* of the section 16.

These cams 39 and 40, as illustrated in Figure 3 of the drawings, are within the straight portion *b* of the section 16 and are spaced apart lengthwise of said portion *b* for any suitable distance preferred.

In the embodiment of my invention as illus-

trated in Figure 8 the links 41 and more especially the innermost of said links are cylindrical in form and extend within a tubular housing 42 supported in any desired manner for rotation. The innermost of the links 41 is operatively connected, as at 43, with a cylindrical member or block 44 which is provided with the peripheral threads 46 of the revolving housing 42. The housing 42, as herein disclosed, is provided with a gear 47 adapted to be engaged with any desired source of power whereby the housing 42 may be rotated as desired in either direction. Upon rotation of the housing 42 in one direction the links 41 of the leg will be moved outwardly and, of course, upon rotation of the housing in the opposite direction the leg will be retracted.

I do not wish to be understood as limiting myself to the particular use to which my improved jack may be put. However, the same can be advantageously employed in connection with a motor driven vehicle and in such connection a desired number of my jacks will be mounted upon the desired portions of the vehicle and the shaft 10 operatively engaged with a preferred moving part of the vehicle. This is also true in connection with the housing 42 as comprised in the embodiment of my invention as illustrated in Figure 8.

From the foregoing description it is thought to be obvious that a jack constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A jack including a housing having its opposite end portions angularly related and its intermediate portion arcuate, a flexible leg movable into and out of the housing through an end thereof, said leg comprising a plurality of links, each of the intermediate links being provided at one end with spaced arms and at its opposite end with a lug, the lug extending between the arms of an adjacent link, means for pivotally connecting the lug and arms of an adjacent link, a T slot disposed through the lug, one of the arms having an opening registering with the head of the T slot of the lug therebetween when adjacent links are substantially aligned, an elongated rigid member slidably mounted in the head of the T slot of the lug, the body of the link having a transverse groove therethrough which has communication with the leg of the T slot of the lug, a stem carried by the rigid member at an extremity thereof and freely received within the leg of the T slot, oppositely disposed arms extending laterally from the stem, the said arms of the stem having sliding engagement within the transverse groove in the body of the link, said arms of the stem being of such length to have one of said arms fully retracted within the body of the link when the other arm of the stem is extended therebeyond, the sliding member, stem and arms of the stem constituting a unit for recurrent movement transversely of the link, and means carried by the housing for contact with an extending arm of the stem for moving the

sliding member in a direction to engage in the opening of one of the arms of a link to lock adjacent links against relative swinging movement or to release adjacent links for relative swinging movement.

2. A jack including a housing having its opposite end portions angularly related and its intermediate portion arcuate, a flexible leg movable into and out of the housing through an end thereof, said leg comprising a plurality of links, each of the intermediate links being provided at one end with spaced arms and at its opposite end with a lug, the lug extending between the arms of an adjacent link, means for pivotally connecting the lug and arms of an adjacent link, a T slot disposed through the lug, one of the arms having an opening registering with the head of the T slot of the lug therebetween when adjacent lugs are substantially aligned, an elongated rigid member slidably mounted in the head of the T slot of the lug, the arms having transversely aligned openings for communication with the leg of the T slot of the lug therebetween, a stem carried by the rigid member at an extremity thereof and freely received within the leg of the T slot, oppositely disposed arms extending laterally from the stem, the arms of the link between which the lug is received having openings through which the arms of the stem pass, said arms of the stem being of such length to have one of said arms fully retracted within the body of the link when the other arm of the stem is extended therebeyond, the sliding member, stem and arms of the stem constituting a unit for recurrent movement transversely of the link, the side faces of the links having grooves extending therealong, and cams carried by opposed walls of the housing and extending within the grooves along the side faces of the links to engage an extended arm of the stem for moving the sliding member in a direction to engage within the opening of one of the arms of a link to lock adjacent links against relative swinging movement or to release adjacent links for relative swinging movement.

3. A jack including a housing having its opposite end portions angularly related and its intermediate portion arcuate, a flexible leg movable into and out of the housing through an end thereof, said leg comprising a plurality of links, each of the intermediate links being provided at one end with spaced arms and at its opposite end with a lug, the lug extending between the arms of an adjacent link, means for pivotally connecting the lug and arms of an adjacent link, a T slot disposed through the lug, one of the arms having an opening registering with the head of the T slot of the lug therebetween when adjacent lugs are substantially aligned, an elongated rigid member slidably mounted in the head of the T slot of the lug, the arms having transversely aligned openings for communication with the leg of the T slot of the lug therebetween, a stem carried by the rigid member at an extremity thereof, and freely received within the leg of the T slot, oppositely disposed arms extending laterally from the stem, the arms of the link between which the lug is received having openings through which the arms of the stem pass, said arms of the stem being of such length to have one of said arms fully retracted within the body of the link when the other arm of the stem is extended therebeyond, the sliding member, stem and arms of the stem constituting a unit for recurrent movement transversely of the link, the side faces

of the links having grooves extending therealong, and cams carried by the opposed walls of the housing and extending within the grooves along the side faces of the links to engage an extended arm of the stem for moving the sliding member in a direction to engage within the opening of one of the arms of a link to lock adjacent links against relative swinging movement or to release

5 adjacent links for relative swinging movement, said cams being spaced apart lengthwise of the housing adjacent to the end beyond which the leg extends, one of said cams operating to lock adjacent links as the leg moves outwardly from the housing and the other for releasing the links after they move inwardly of the housing.

CLARENCE M. DONAHOO.
